(57) **CLAIM**

I claim the ornamental design for the ion generating lamp, as shown and described.

DESCRIPTION

FIG. 1 is a perspective view of the invention

FIG. 2 is a front view of the invention

FIG. 3 is a rear view of the invention

FIG. 4 is a side view of the invention

FIG. 5 is a top view of the invention; and,

FIG. 6 is a bottom view of the invention.

The portions of the ion generating lamp shown in broken lines form no part of the claimed design.
